CHEST

Ernest Herrmann, Hillsdale, N. J., assignor to The Mengel Company, Louisville, Ky., a corporation of New Jersey

Application August 5, 1952, Serial No. 20,910

Term of patent 7 years

(Cl. D33—19)

To all whom it may concern:

Be it known that I, Ernest Herrmann, a citizen of the United States of America and a resident of Hillsdale, in the county of Bergen, State of New Jersey, have invented a new, original, and ornamental Design for a Chest, of which the following is a specification, reference being had to the accompanying drawing, forming a part hereof.

Figure 1 is a perspective view of a chest embodying my new design;

Figure 2 is another perspective view of the same chest; and

Figure 3 is a perspective view similar to Figure 2 but with the panel doors open.

I claim:

The ornamental design for a chest, as shown.

ERNEST HERRMANN.
